UNITED STATES PATENT OFFICE.

ADOLPH H. SOMMERS, OF HAZLETON, PENNSYLVANIA.

BED ATTACHMENT.

SPECIFICATION forming part of Letters Patent No. 739,452, dated September 22, 1903.

Application filed December 17, 1902. Serial No. 135,615. (No model.)

To all whom it may concern:

Be it known that I, ADOLPH H. SOMMERS, a citizen of the United States, residing at Hazleton, in the county of Luzerne and State of

5 Pennsylvania, have invented certain new and useful Improvements in Bed Attachments; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 My invention relates to bed attachments, and has for its object to provide a device which will quickly and easily form a partition for beds or the like.

A further object of my invention is to provide 20 a device for the above purpose which may be used on floors at top of steps in order to prevent children from falling down or which may be employed in any capacity where a removable partition is desired.

25 My invention may also be employed as a fence or gate when constructed on a larger scale.

With this object in view my invention consists in the particular adjusting arrangement 30 of my device, and also in certain other novel features of construction and in combination of parts, which will be first fully described and afterward specifically pointed out in the appended claims.

35 Referring to the accompanying drawings, Figure 1 is an elevation showing application of my invention. Fig. 2 is an enlarged fragmentary view of front of rack, showing securing-pin in section and several positions thereof in dotted lines. Fig. 3 is a detail of rack-plate. Fig. 4 is a vertical section through the 40 rack and securing-pin, and Fig. 5 is a fragmentary detail of a modification of upper end of partition.

45 Like numerals of reference indicate the same parts throughout the several figures, in which—

1 is a bed, and 2 and 3 indicate the head and foot boards.

50 4 is my partition, composed of the head-section 5 and foot-section 6, said sections being provided with rubber ends 7 or some other

soft or yielding material to prevent scarring of the bedstead and to increase the friction between the same and the partition, thereby 55 increasing the stability of the same.

8 indicates my rack-plate, which is let into the inner side of the head-section 5, and 8 is the outer plate. Said rack-plate is provided with an upper and lower series of notches 9 and 60 projections 10, which are so arranged that an upper notch 9 is opposite a lower projection 10, and the opposite corners of said projections are cut away at 11.

The foot-section 6 is provided with a circular opening 12, surrounded by an annular plate or washer 13 on the inner side and an annular recessed plate 14 on the outer side thereof.

15 indicates my securing-pin, which is flattened at 16 and threaded at 17, a nut 18 holding the pin in position. 19 indicates a folding head on said pin, (shown in a folded position at 19' in Fig. 4,) and 20 is a washer 70 between said head and outer plate. 75

In Fig. 5 I show the extreme upper portion of head-section 5 so constructed as to allow for an opening or recess 21 in the end thereof, thus forming the bifurcated end 22', each part of which is provided with a rubber or 80 other resilient piece 23 for the purpose before described. The object of this modification is to allow the partition to straddle the bolster or pillow of the bed, so as not to interfere with the same. 85

Having thus described my invention, the operation is as follows: The securing-pin 15 is turned so that the flattened portion 16 is horizontal. While in this position said pin may readily be moved along the slot or opening 22 in the rack-plate 8. The partition is placed on the bed, as shown in Fig. 1, and said securing-pin, which is not laterally movable in the foot-section 6, is moved within the rack-plate 8 by drawing the head and foot 95 sections 5 and 6 apart or bringing them together. When the desired length of said partition is obtained, the securing-pin 15 is turned so that the flattened portion 16 is vertical, which causes said flattened portion to 100 enter one of the notches 9 in the rack-plate, as shown in Fig. 2, either in the head or lower series, according to the position of said pin when the desired adjustment is secured. The

center of the partition is then depressed, which brings said partition into position shown in dotted lines in Fig. 1 and firmly and securely holds the same in contact with the head and foot boards. When it is desired to remove the partition, the head-section 5 is grasped in the hand-opening 23 and raised, which quickly disengages the partition. In order to set away out of use, the two sections are folded over each other, which allows for compact storage or shipment. It is obvious that a spreading device of great power can be constructed on these lines, and I consider myself clearly entitled to all such uses.

Having thus described my invention, I do not wish to be understood as limiting myself to the exact construction herein set forth, as various slight changes may be made therein which would fall within the limit and scope of my invention, and I consider myself clearly entitled to all such changes and modifications.

What I claim as my invention, and desire to secure by Letters Patent of the United States, is—

- 25 1. In a bed attachment the combination with the head and foot sections, of a rack-plate in the head-section, a securing-pin adapted to pass through said rack-plate, and through the foot-section.
- 30 2. In a bed attachment, the combination with the sections of a rack-plate in one of said sections, provided with two series of notches and a securing-pin adapted to pass through said rack-plate and through the other section.

3. In a bed attachment, the combination 35 with the two sections, of a rack-plate provided with a slot therein, a series of notches on each side of said slot, and means passing through said rack-plate for securing the said sections together.

4. In a bed attachment the combination 40 with a fixed section, of a movable section, a rack-plate thereon provided with a slot therein, a series of notches and projections on each side of said slot, the said notches on one series being opposite the projections on the other, and means passing through said rack-plate for securing the sections together.

5. In a bed attachment, the combination 45 with the head and foot sections, of a rack-plate on one of said sections, provided with a slot therein, a series of projections on each side of said slot, said projections having cut-away corners for the purpose described, and means passing through said rack-plate for securing the sections together.

6. In a bed attachment, the combination 50 with the foot-section of a head-section pivoted thereto, means for sliding one of the sections on said pivot to adjust the length of the 60 two sections.

In testimony whereof I affix my signature in presence of two witnesses.

ADOLPH H. SOMMERS.
